Glovesky and Popeo, P.C.

(57)

CLAIMThe ornamental design for a food preparation device, as
shown and described.**DESCRIPTION**FIG. 1 is a perspective view of a food preparation device;
FIG. 2 is a front view of the device shown in FIG. 1;
FIG. 3 is a rear view of the device shown in FIG. 1;
FIG. 4 is a side view of the device shown in FIG. 1;
FIG. 5 is another side view of the device shown in FIG. 1;
FIG. 6 is a top view of the device shown in FIG. 1; and,
FIG. 7 is a bottom view of the device shown in FIG. 1.
The broken lines are shown for the purpose of illustrating
parts of the article that form no part of the claimed design.**1 Claim, 7 Drawing Sheets**| (56)	References Cited
